UNITED STATES PATENT OFFICE.

DWIGHT F. KILGOUR, OF LEXINGTON, MASSACHUSETTS.

LUBRICATOR.

1,242,702.

Specification of Letters Patent.

Patented Oct. 9, 1917.

Application filed August 21, 1916. Serial No. 115,925.

To all whom it may concern:

Be it known that I, DWIGHT F. KILGOUR, a citizen of the United States, and a resident of Lexington, in the county of Middlesex and Commonwealth of Massachusetts, have invented an Improvement in Lubricators, of which the following description, in connection with the accompanying drawings, is a specification, like characters on the drawings representing like parts.

This invention relates to lubricators for the guide rails of elevators and other purposes. It is an improvement upon the lubricator shown in Letters Patent No. 1,089,060, granted to me March 3, 1914.

The character of the invention may be best understood by reference to the following description of an embodiment thereof illustrating the invention shown in the accompanying drawings, wherein,—

Figure 1 is a side elevation of an elevator guide shoe and rail and a lubricator illustrating the invention mounted on said shoe;

Fig. 2 is a plan of the lubricator with its neck removed;

Fig. 3 is a rear elevation of the lubricator shown in Fig. 1;

Fig. 4 is a plan of the lubricator;

Fig. 5 is a front elevation of the lubricator;

Fig. 6 is a plan of a modified form of wick-supporting neck;

Fig. 7 is a front elevation of the neck shown in Fig. 6;

Fig. 8 is a plan of another form of wick-supporting neck; and

Fig. 9 is a front elevation of the neck shown in Fig. 8.

Referring to the drawings, the lubricator shown therein as illustrating the invention comprises a receiver 1, conveniently cast from metal in cylindrical form with a top 3 preferably integral therewith. The reservoir may be provided with a thick wick 4 for conducting the lubricant therefrom to the rail or other thing to be lubricated. To support and guide the wick a neck 5 is provided curved upward and forwardly from the top of the reservoir. The lower end of said neck may terminate in an elongated base 7 having a flange 9 fitting into an elongated aperture in the top of the reservoir and serving as a cover therefor. The neck preferably tapers forwardly as well shown in Fig. 4 to present a constricted portion 11 to

nip the wick and suitably hold the same in said neck.

The neck may be readily adjusted to expose the opening in the top and allow lubricant to be poured into the reservoir therethrough. To accomplish this the reservoir may have a lug 13 (Figs. 1 and 5) cast thereon and the neck may have a pair of ears 15 depending therefrom connected to said lugs by a hinge pin 17 which may be detachable for a purpose to be described. The neck may readily swing in a contraclockwise direction (Fig. 1) about said pin as a fulcrum and expose the top opening.

To normally hold the neck in position for use with its base closing said opening, suitable latch means may be provided, typified herein as a coil spring 19, having one end attached to an eye in a lug 20 on the reservoir adjacent the top thereof and its other end curved to present a loop adapted to be inserted in an open eye 21 in a lug projecting rearward from said neck.

This spring will hold the neck base securely onto the reservoir top and prevent rattling of the parts, but may be readily released from the eye 21 to permit opening of said base.

The spring 19 not only forms a convenient latch for holding the neck base closed, but also permits a limited rocking movement of the neck in a contraclockwise direction in case the wick or the forward edge of the neck in traveling along an elevator guide rail, strikes an obstruction, such for example, as a shoulder at the union of adjacent rails. The spring will permit the neck to rock and prevent injury to the lubricator from such cause.

Preferably the neck is of cast-iron or other heavy construction. With the fulcrum pin adjacent the left end of said neck (Fig. 1) the preponderance of the weight thereof is at the right of said fulcrum pin and assists the spring 19 in holding the neck base normally seated over said top opening.

The lubricator is illustrated herein as cooperating with a guide rail 23 of an elevator well along which the usual shoe 25 of an elevator car (not shown) is adapted to slide. To support the lubricator from said shoe or other device in connection with which the same is used, a bracket 27 may be provided having a flange 29 with a pair of eyes through which bolts 31 are entered and secured.

cured to said shoe. A base member 33 may be mounted on said bracket and be provided with tandem lugs 35 depending therefrom, adapted to slide in an elongated slot in said bracket and allow said base to be adjusted toward and from the rail to vary the distance of the lubricator therefrom as required. To secure said base to said bracket a screw bolt 37 may be tapped in one of said base lugs 35 and press a clip 39 against the bottom of the bracket. This clip may have sufficient spring to allow the same to be tensioned and securely hold the parts together.

The lubricator shown in my patent referred to was pivoted to its bracket by a single lug located centrally, laterally beneath the lubricator. This allowed more or less wabbling of the lubricator and did not give it the stability desired. To overcome this objection the lubricator shown herein may be provided with a pair of ears 41 depending therefrom, widely spaced and preferably adjacent the sides of the lubricator. The base 33 referred to may have a pair of bosses 43 projecting upward therefrom and a horizontal shaft 45 may be entered through registering holes in said ears and bosses and be secured in position by cotter pins 47. The ears 41 are located somewhat to the rear of a vertical plane passing through the center of gravity of the lubricator so that the weight of the latter will tend to rock the same automatically in a contraclockwise direction (Fig. 1) and press the wick against the rail. This will serve normally to maintain the wick against the rail with a desired nicety of pressure to feed the appropriate amount of lubricant from the reservoir through the wick to the rail.

To limit rocking of the lubricator away from the rail, a stop may be provided conveniently in the form of a spring arm 49 having its lower end secured to the lubricator base 33 and its upper end free and adapted for engagement with the reservoir. Normally there will be a slight space between said arm and said reservoir, but if the reservoir swings backward away from the rail it will be limited by said spring arm and the inherent resilience of the latter when thus energized will automatically return the reservoir toward the rail to bring its wick again in engagement therewith. Thereupon the weight of the reservoir, offset on its fulcrum as described, will serve again to urge the wick toward said rail.

When the lubricator is to remain out of use for any considerable period it is desirable to adjust the same away from the rail to prevent engagement of its wick therewith. This will prevent excess lubricant from being drawn by capillary attraction through the wick to the rail. For this purpose a lock arm 51 may be provided fast

on a shaft 53 journaled in a bore in said base 33 and having a handle 55 for controlling the same. When the lubricator is in use said arm is rocked to its position shown in full lines in Fig. 1, but when it is to be held out of operation, it is rocked in a clockwise direction up against the bottom of the reservoir to a position shown in dotted lines in Fig. 1, in which it is somewhat beyond the dead center of said shaft. In the course of this movement said arm will rock said reservoir back against said spring arm 49 and thereby tension the latter so that said spring arm will serve to maintain the reservoir against said lock arm and hold the latter in its active position.

Various necks may be provided for the lubricator according to the form of wicks required.

In Figs. 6 and 7 is shown a neck 57 similar to that shown in Fig. 1 with the exception that instead of being flattened vertically it is wider and flattened horizontally. The base 59 of the neck 57 may be the same as that of the neck 5, so that it may readily fit the opening in the top of the reservoir and be substituted therefor. To accomplish this substitution, it is merely necessary to release the latch spring 19, withdraw the pin 17, and substitute the neck 57 for the neck 5.

In some cases it may be desirable to have the wick engage not only the front edge of the rail, but also the sides of the rail. To accommodate such a wick a neck 61 may be provided as shown in Figs. 8 and 9. This neck has outer, tube-like portions 63 and an intermediate, tube-like portion 65. The former receive wicks 67 for engagement with the sides of the rail, and the latter receives a wick 69 for engagement with the edge of the rail. The side wicks have ends projecting somewhat beyond the intermediate wick supported by extensions 63^a at the outer sides thereof. The neck 61 may be provided with a base 71 similar to the bases of the first two necks described, so that the neck 61 may be readily substituted for the others.

It will be apparent that the parts are so standardized that the various substitutions may be quickly and readily made without any change in the construction or without the use of a tool.

While the lubricator has been described herein more particularly in connection with its use for lubricating elevator rails, it will be understood that it is not limited thereto, but may be used for lubricating shafts and other purposes.

Having described one illustrative embodiment of the invention without limiting the same thereto, what I claim as new and desire to secure by Letters Patent is:

1. A lubricator comprising a reservoir, a top therefor carrying a holder thereon adapted to receive a wick, and means piv-

totally connecting said top and said holder with said reservoir.

2. A lubricator comprising a reservoir 1, a holder thereon for receiving a wick, and means 13, 15, 17 pivotally and detachably connecting said holder with said reservoir.

3. A lubricator comprising a reservoir, a top therefor carrying a holder thereon for receiving a wick, and means 19, 21 allowing a limited movement of said top and said holder relatively to said reservoir.

4. A lubricator comprising a reservoir 1, a holder thereon for receiving a wick, means 13, 15, 17 pivotally connecting said neck with said reservoir, and spring means 19 permitting a limited tilting movement of said holder relatively to said reservoir.

5. A lubricator comprising a reservoir, a holder thereon adapted to receive a wick, means pivotally connecting said holder with said reservoir, and spring latch means connecting said holder with said reservoir having provision permitting a limited tilting movement of the former relatively to the latter.

6. A lubricator comprising a reservoir, a holder for receiving a wick, ears on said reservoir and holder, and a pivot pin detachably connecting said ears.

7. A lubricator comprising a reservoir having means for guiding a wick therefrom, a bracket, a base carrying said reservoir and adapted to slide longitudinally of said bracket, and spring means for securing said base to said bracket.

8. A lubricator comprising a reservoir having means to guide a wick therefrom, a bracket having an elongated slot therein, a base carrying said reservoir and having lugs adapted to slide in said slot, and means including a spring clip for securing said base to said bracket.

9. A lubricator comprising a reservoir 1 provided with a top having an opening therein, a wick neck 5 having a base for closing said opening and curving upwardly and forwardly from said top, means including a pin 17 pivotally connecting said neck with said reservoir, means 19 for yieldingly

holding said base on said top, a support 33, 50 and means pivotally connecting said reservoir with said support.

10. A lubricator comprising a reservoir having an opening therein, a wick holder fitting said opening and projecting upward 55 and forward therefrom, with an outer end for presenting the end of a wick beyond the side of said reservoir, and means adjacent said outer end for pivotally connecting said holder with said reservoir, whereby the 60 weight of said holder tends to hold the same over said opening.

11. An elevator guide lubricator comprising, in combination, a reservoir carried by the elevator car, a removable top therefor 65 carrying a wick and a wick-holder, said top, wick and wick-holder being removable as a unit, and securing means opposing displacement of said top and the parts carried thereby.

12. An elevator guide lubricator comprising, in combination, a reservoir, a pivotal support therefor carried by a part moving with the elevator and permitting tipping of the reservoir to and from the front of the 75 guide, a removable top for said reservoir carrying wick-holding means, wicks for lubricating a plurality of surfaces of the guide, said top, wick-holding means and wicks being separable as a unit from said 80 reservoir, and securing means opposing displacement of said top and the parts carried thereby.

13. A lubricator comprising, in combination, a reservoir, a pivotal support therefor, 85 and a top for said reservoir carrying a laterally projecting wick-holder and wick, said top, wick-holder and wick being removable as a unit.

14. Lubricator equipment comprising a 90 reservoir having a wick opening therein, holders for a single wick or a plurality of wicks respectively, and hinge and latch means for detachably connecting said holders to said reservoir.

In testimony whereof, I have signed my name to this specification.

DWIGHT F. KILGOUR.
